CLAIM

The ornamental design for a gaming machine with curved display, as shown and described.

DESCRIPTION

FIG. 1 is a right isometric view of a gaming machine with curved display showing our new design;

FIG. 2 is a left isometric view thereof;

FIG. 3 is a front view thereof;

FIG. 4 is a right side view thereof;

FIG. 5 is a top view thereof; and,

FIG. 6 is a left side view thereof.

The broken line showing of the remainder of the gaming machine with curved display illustrates environmental structure and forms no part of the claimed design. The oblique
